UNITED STATES PATENT OFFICE.

GEORGE F. ALBRECHT AND HARRY BROOK, OF WOONSOCKET, RHODE ISLAND, AS
SIGNORS TO WOONSOCKET MACHINE & PRESS CO., INC., OF WOONSOCKET, RHODE
ISLAND, A CORPORATION OF RHODE ISLAND.

ROVING FRAME.

Application filed December 7, 1923. Serial No. 679,183.

To all whom it may concern:

Be it known that we, GEORGE F. ALBRECHT and HARRY BROOK, citizens of the United States, residing at Woonsocket, in the county 5 of Providence, State of Rhode Island, have invented a certain new and useful Improvement in Roving Frames, of which the following is a specification, reference being had therein to the accompanying drawings.

10 The features of the invention apply in connection with the chain-drive mechanism employed in fly-frames, such as roving frames, more particularly that employed for driving the so-called bobbin-shafts, i. e., bobbin driving shafts; with the supporting bearings of the said shafts; and with the 15 cover for the drive-chain and the sprocket-wheels with which it engages.

The invention comprises an improvement 20 in connection with the tightener-roll devices of chain-drive mechanism; also an improvement in connection with the bearings for the butts or end-sections of the said shafts; and also an improvement in the means of supporting the cover aforesaid in proper 25 relations with the parts which it encloses.

The first improvement applies in the case 30 of chain-drive mechanisms of the type comprising a sprocket-chain connection between a sprocket-wheel that does not traverse up and down and one or more sprocket-wheels that are carried up and down by the traverse-rail in its traversing movements. It is herein embodied in a one-step sprocket-chain connection between a driving sprocket-wheel that is actuated through a fly-frame compound or differential, and a driven sprocket-wheel upon one or each of the bobbin-shafts of the fly-frame. It has been proposed heretofore to provide a chain-drive 35 mechanism of such type with a movably mounted tightener-roll which engages with the said sprocket-chain intermediate the driving sprocket-wheel and the driven sprocket-wheel or wheels for the purpose of taking up slack in the chain and paying out chain as the distance of the driven wheel or wheels from the driving wheel varies in the movement of the traverse-rail up and down. The 40 said tightener-roll is intended to take up the slack forming in the chain as the traverse-rail moves from either limit of the traverse toward an intermediate point of the latter, and to pay out the chain again as the trav-

erse-rail continues from the said intermediate point toward the other limit of the traverse.

Different forms of bobbin-shaft chain-drive mechanisms of the type just specified are shown, described, and claimed in the applications for United States Letters Patent therefor filed in the name of George F. Albrecht, one of the present inventors, namely Serial No. 662,669, filed Sept. 14, 1923; Serial No. 664,510, filed Sept. 24, 1923; and Serial No. 664,511, filed Sept. 24, 1923.

In conformity with the first improvement aforesaid, a bobbin-shaft chain-drive mechanism of the said type is provided with means for positively controlling the tightener-roll 70 so as to cause it to operate in proper correlation with the up and down movements of the traverse-rail. The said means preferably consists in a tightener-roll controlling cam.

One object of the said first improvement 75 is to provide an improved tightener-roll device for the said chain-drive mechanism. Another is to provide a positively controlled tightener-roll. One purpose of the invention is to provide a tightener-roll device 80 which shall have equal effectiveness in taking up slack, whether the drive-chain is caused to travel in one direction or the reverse direction, as for instance whether the chain travels in the direction for causing the bobbins to be rotated in the proper direction for imparting a right hand twist to the rovings, or is caused to travel in the reverse direction 85 in order to cause the bobbins to be rotated reversely for imparting a left hand twist. 90 This improvement renders it practicable by means of the chain-drive to drive the bobbin-shafts in either the direction required for putting right hand twist into rovings, or in the reverse direction, either for putting 95 left hand twist into rovings or for enabling a roving frame to be operated as a twister.

The improvement in connection with the bearings for the butts or end-sections of the bobbin-shafts of a roving frame provides 100 for greater convenience in assembling the said bearings and the said butts or end-sections in proper working relations with the slide at the head-end of the traverse-rail, and in disassembling the parts.

105 The improvement in connection with the cover aforesaid provides improved means for supporting it in proper relations with the

drive-chain and the driving sprocket that is combined with the sleeve of the compound or differential.

5 Embodiments of the features of the invention are illustrated in the drawings, in which latter,—

Fig. 1 is a view of a portion of a roving frame having the improvements applied thereto, in section in a vertical plane extending 10 from front to rear.

Fig. 2 is a plan view of the parts which are shown in Fig. 1, with the top cover-sections removed or partly broken away.

15 Fig. 3 is a view, partly in section on line 3—3 of Fig. 2, looking in the direction indicated by the arrows at the ends of such line.

Fig. 4 is a view in vertical section on line 4—4 of Fig. 3.

20 Figs. 5, 6 and 7 are detail perspective views.

Fig. 8 shows a grooved tightener-roll actuating cam.

Fig. 9 is a view in section on line 9—9 of Fig. 2.

25 The drawings do not show the usual traverse-rail of a roving frame, but they do show the features of the invention applied in connection with a rail head-end slide 1 (illustrated separately in Fig. 5) which, in practice is connected with the head end of said rail, its outer side having as usual a groove 11 receiving a vertically-extending guide-rib 2 (Figs. 1, 2, 3) upon the head 3 (Figs. 1 and 2) of the machine-frame, on which 30 guide-rib the slide moves up and down in the vertical traversing movements of the traverse-rail. The drawings show also the cover-sections 21, 22, Figs. 1, 2, 3, 4, constituting the bobbin-shaft gear-box and attached to the said slide by means of suitable 35 bolts 111, 111, and in addition show the so-called butts or end-sections 4, 4, of the two bobbin-shafts which are associated with the traverse-rail, they being mounted in bearings 5, 5, and 51, 52, Figs. 2, 3, and 4, in connection with the bottom cover-section 21 and the said slide 1. The said bobbin-shafts, 40 two in number as required for the driving of the two longitudinal lines of bobbins surrounding the two longitudinal lines of flier-spindles employed in a roving frame, are driven through the illustrated chain-drive connections from sprocket-wheel 61 fixed upon the sleeve 6, Figs. 1, 2, 3, surrounding 45 the main shaft 7, the said sleeve being an element of the compound or differential of the roving frame, and being driven in well-known manner at progressively varying 50 speed in the operation of the roving frame.

In practice, the chain-drive mechanism in connection with which the first improvement is applied may vary in different respects, as 55 will appear from the three patent applications to which reference has been made.

The accompanying drawings illustrate only one of the different forms of chain-drive mechanism to which the said improvement is applicable. The illustrated form includes the two driven sprocket-wheels 8, 8, Figs. 1, 2 and 4, which respectively are fixed upon the respective butts or end-sections of the bobbin-shafts, and a sprocket-chain 9, Figs. 1 and 2, constituting a one-step driving-chain connection between sprocket-wheel 61 and sprocket-wheels 8, 8. The said sprocket-chain extends part way around the driving sprocket-wheel 61, in engagement with the latter, one run of the chain being extended from the lower portion of wheel 61 forward 70 beneath both of the sprocket-wheels 8, 8, and in direct engagement with the lower portions of both, the chain then extending part way around the wheel 8 of the forward bobbin-shaft, and its upper run extending 75 rearward above both wheels 8, 8, to the upper portion of the wheel 6. The total length of the chain 9 is sufficient to permit the required extent of up and down traverse movements of the traverse-rail to occur. 80 When the driving sprocket-wheel 61 rotates in the direction indicated by the full-line arrow marked thereon, the upper run of the drive-chain is the taut working run; the lower run is the idle or return run. A 85 tightener-roll 90 acts upwardly against the under side of the said lower run. As in the case of the various chain-drive mechanisms of the applications which have been mentioned the said tightener-roll is employed for the purpose of taking up such slack as may tend to form in the chain as the traverse-rail moves from either limit of its traverse toward the middle point of the traverse, thereby keeping the idle or return 90 run from slatting loosely up and down, and holding the chain in proper engagement with the rear bobbin-shaft wheel 8. The tightener-roll yields up slack as the traverse-rail nears either limit of its traverse 95 and the drive-chain tautens. As in the patent applications aforesaid the tightener-roll 90 in this instance is journaled in the arms of a cradle or hanger 10 that is mounted in such relations with the rear bobbin-shaft 8 100 that it swings concentrically around such shaft. As a convenient construction for the embodiment of the first improvement comprised in the present invention, one side-arm of said cradle or hanger is herein fitted to the inner bearing, 5, of the rear bobbin-shaft with capacity to rock thereon, and the other side-arm, as shown in Fig. 4, is fitted 105 upon and keyed to the outer bearing, 52, of such shaft, so that bearing 52 and cradle 110 or hanger 10 shall rock in unison. This construction provides for the said rocking movement of the cradle or hanger 10 around the rear bobbin-shaft 8. In its taking-up 115 movement, such movement being upward in 120 125 130

the case of the illustrated construction, the tightener-roll tends to wrap the slack or idle run of the drive-chain more completely around the rear sprocket-wheel 8. The weight of the portion 101 of the cradle or hanger 10 at the front of the rear bobbin-shaft may be sufficient to counterbalance more or less completely that of roll 90, etc., at the rear of said shaft, and, in addition, the weight of the lower run of the chain, or an equivalent spring may be employed for such purpose. The effect of such weight, or spring, acting at the front of the rear bobbin-shaft 4, may be sufficient to overbalance the weight of the roll, etc., at the rear of such shaft so that, in the case of the construction shown in Figs. 1 to 4, when the drive-chain moves in the direction indicated by the full-line arrow on sprocket-wheel 61 in Fig. 1, the roll will be actuated yieldingly to take up such amount of the slack as may not be taken up through the action of the controlling cam.

A yieldingly actuated tightener-roll will not give satisfactory results when driving sprocket-wheel 61 rotates in the reverse direction, namely the direction indicated by the dotted line arrow in Fig. 1. In such case the pull acts through the lower run, tightening the latter, and this action would have the effect of forcing the tightener-roll down, permitting objectionable slack to form in the upper run in proportion to the straightening of the lower run. For this reason, the invention makes provision for positive control of the tightener-roll so as to prevent it from ceasing to function when the direction of rotation is reversed.

The drawings show positive controlling means constituted by a cam, which may be either an edge cam 12 as in Figs. 1, 2, 3, 4, or a grooved cam 125 as in Fig. 8. In the case of the former the working edge 121, and in the case of the latter a wall of the groove 126, cooperates with a follower-roll 122 carried by an arm 123, Figs. 1, 2, 3, 4, and 6, projecting from the bearing 52. Each of the said cams is shaped to provide for rocking movement of the cradle or hanger 10 to take up slack in the chain in the first part of a traverse in either direction, and to pay out chain in the latter portion of such traverse. The edge cam 12 will ensure the required action of the tightener-roll, while leaving the latter free to be actuated by overweighted portion 101 of cradle or hanger 10 to take up any slack in excess of that taken up through the action of the cam. In the case of the grooved cam 125 the action of the overbalancing weight or spring is not so important unless the cam-groove is wide enough to permit considerable play of the follower-roll 122 transversely of the groove.

In general practice, when a yieldingly

actuated tightener-roll is combined with a sprocket-chain it is arranged to act against the slack run of the chain. It is not combined with the tight working run of the chain, because the tension of the said run would render the roll ineffective as a means of taking up. This latter fact would render the yieldingly actuated tightener-roll of no avail in the case of a reversal of the direction of movement of the drive-chain. Consequently the chain-drive arrangements of the patent applications hereinbefore mentioned are adapted for driving the bobbin-shafts in one direction only. They do not

permit of driving the bobbin-shafts in the reverse direction, inasmuch as reversal of the direction of movement of the drive-chain would render the yieldingly actuated tightener-roll of such arrangements ineffective to control the slack of the drive-chain. This is due to the fact that in the case of such reversal the previously slack run engaged by the tightener-roll would become the working run and would tighten so that the consequent tension thereof would be too great to permit the tightener-roll to have sufficient effect thereon to take up the chain. Slack would form in the opposite run, the latter having now become the slack run. In the case of a cam-controlled tightener-roll, however, the position of such roll is determined by the controlling cam, which renders the action positive in taking up slack. Consequently, reversal of the direction of movement of the chain does not interfere with the performance of the taking-up function; the cam continues to actuate the roll to take up slack in the chain. In operation the tightener-roll will bend the chain upward to properly varying extents between said sprocket-wheel 61 and the rear driven sprocket-wheel 8, and thereby prevent the downward displacement of the tightener-roll and consequent slackening of the top run of the chain that would result in the absence of such control.

Referring now to the improvement in bobbin-shaft bearings. The said improvement applies in connection with the bearings 51, 52, next adjacent the frame-head 3. The closeness of the slide 1 to the said head is such as to make it inconvenient to effect endwise insertion or removal of a bearing. In accordance with the present invention open topped bearing-receiving pockets 151, 151, Figs. 2, 3, 4, 5, are provided in connection with slide 1, to receive the said bearings 51, 52. Provision is made for holding the bearings in place within the pockets 151, 151. In this instance the lower edge of cover-top 22 holds the bearings from rising. In the absence of the cover-top the bearings may be put into the pockets by dropping them in from above and removal may be effected by lifting them up out of

the pockets. When the cover-top is in place it secures the bearings and the butts or end-sections of the bobbin-shafts in working position. A radial shoulder 53 on each bearing 5 acts, through engagement with the inner side of the slide, to prevent displacement of the bearings endwise toward head 3. The inner portion 54 of each bearing serves as a spacer between the slide and the hub of the corresponding bobbin-shaft sprocket-wheel 8, to prevent endwise movement of the corresponding bobbin-shaft toward the head 3. The top of bearing 51 is slabbed off, as shown best in Fig. 7, so that through the engagement of the lower edge of cover-top 22 with the flat upper surface of said top the said bearing is held from rotating with the corresponding bobbin-shaft. The bearing 52 is rounded off on top to permit the same to turn under the said lower edge, as necessary for the operation of the tightener-roll 90. Such bearing is restrained from turning in unison with the corresponding bobbin-shaft 25 through its connection with the cradle or hanger 10 and also through the contact of roll 122 of arm 123 with the acting edge of the roll-controlling cam.

The cover-sections 93, 94, for the driving sprocket-wheel 61 and the adjacent portions of the drive-chain 9 are secured together by means of the bolts 95, 95, a forward extension of the top-section 93 being pivotally engaged at 96, Fig. 1, with slide 1, while the rear portion of said section is furnished with a contact-piece 97, Fig. 3, which rests upon the inner end of a bearing-sleeve or bushing 71 through which the main shaft 7 extends as shown best in Fig. 9. The connected cover-sections 93, 94, thereby are supported at the rear while they rock around such point of support in unison with the up and down traverse-movements of the traverse-rail. The bearing-sleeve or bushing 71 is mounted in connection with head-end 3 of the machine-frame by means of a bearing-plate 72 applied in connection with the head-end. The bushing fits loosely within a hole through the said bearing-plate, being held from rotation by means of a lug 73 projecting radially from the bushing into a notch in the bearing-plate. An annular shoulder 74 on the bushing engages with the edge of the said hole through the bearing-plate 55 to prevent endwise movement of the bushing in one direction, while the inner end of the bushing abuts against the adjacent end of sleeve 6, whereby endwise movement of the bushing in the other direction is prevented. Inasmuch as bushing 71 is a non-rotating part there is no excessive wear between the contact-piece 97 and the bushing, as would be the case if said contact-piece rested upon a revolving member. To hold 60 the cover 93, 94, from sidewise movement,

the bushing is formed with a groove 75 within which the lower edge of the contact-piece is entered.

What is claimed as the invention is:—

1. In chain-driven mechanism, the combination with a driving sprocket-wheel, a driven sprocket-wheel partaking of traverse movements, a drive-chain passing around both of the said sprocket-wheels, and a tightener-roll engaging with said drive-chain intermediate the said sprocket-wheels, of means positively controlling the tightener-roll and causing it to keep the slack taken up during the up and down movements of the traverse. 70

2. In chain-drive mechanism, the combination with a driving sprocket-wheel, a driven sprocket wheel partaking of traverse movements, a drive-chain passing around both of the said sprocket-wheels, and a tightener-roll engaging with said drive-chain intermediate the said sprocket-wheels, of a cam controlling the tightener-roll and causing it to keep the slack taken up during the up and down movements of the traverse. 85

3. In a roving frame, the combination with a driving sprocket-wheel in operative connection with the compound or differential, front and rear vertically-traversing bobbin-shafts respectively having sprocket-wheels, a drive-chain through which said driving sprocket-wheel actuates both of said bobbin-shafts, and a tightener-roll engaging said drive-chain, of means by which as the traverse-movements take place the tightener 100 is actuated in correlation with such movements to keep the slack positively taken up. 90

4. In a roving frame, the combination with a driving sprocket-wheel in operative connection with the compound or differential, front and rear vertically-traversing bobbin-shafts respectively having sprocket-wheels, a drive-chain through which said driving sprocket-wheel actuates both of the bobbin-shafts, and a tightener-roll engaging 105 said drive-chain, of a cam controlling the tightener-roll and keeping slack positively 110 taken up. 110

5. In a roving frame, the combination with a driving sprocket-wheel in operative connection with the compound or differential, a vertically-traversing bobbin-shaft having a sprocket-wheel, a drive-chain through which said driving sprocket-wheel actuates said bobbin-shaft, and a tightener-roll 115 coaxing with said drive-chain, of a non-traversing cam by which the tightener-roll is controlled during the traverse movements to keep slack positively taken up. 120

6. In a roving frame, the combination with a driving sprocket-wheel which does not partake of traverse-movements, a vertically-traversing bobbin-shaft provided with a sprocket-wheel, a drive-chain through which said driving sprocket-wheel actuates 125 130

said bobbin-shaft, and a tightener-roll partaking of the traverse-movements and coacting with the drive-chain, of a stationary cam controlling the tightener-roll so as to keep slack positively taken up.

7. In a roving frame, the combination with a driving sprocket-wheel which does not partake of traverse-movements, a vertically-traversing bobbin-shaft provided with a 10 sprocket-wheel, a drive-chain through which said driving sprocket-wheel actuates said bobbin-shaft, a tightener-roll coacting with the drive-chain, and a tightener-roll cradle mounted concentrically with said bobbin-15 shaft, of a cam by which said cradle is rocked during the traverse-movements so as to keep slack positively taken up.

8. In a roving frame, the combination with a driving sprocket-wheel which does not partake of traverse-movements, a bobbin-shaft having a sprocket-wheel, a vertically-traversing slide, a bobbin-shaft bearing supported by said slide, a drive-chain through which said driving sprocket-wheel 20 actuates said bobbin-shaft, a tightener-roll 25 acting against the drive-chain, a tightener-roll cradle connected with said bearing, and a cam operating to rock said bearing to thereby actuate the tightener-roll to keep 30 the slack positively taken up during the traverse-movements.

9. In a roving frame, the combination with a frame-head, a bobbin-shaft, and a bobbin-shaft bearing, of a vertically-moving 35 traverse-rail slide close beside said frame-head having an open topped pocket for said bearing permitting vertical application and removal of the bearing.

10. In a roving frame, the combination with a frame-head, front and rear bobbin-shafts, and bobbin-shaft bearings, of a vertically-moving traverse-rail slide close beside the said frame-head having front and rear open-topped pockets for said bearings 45 permitting vertical application and removal of the respective bearings.

11. In a roving frame, the combination with a frame-head, a bobbin-shaft, and a bobbin-shaft bearing, of a vertically-moving 50 traverse-rail slide close beside said frame-head having an open-topped pocket for said bearing permitting vertical application and removal of the bearing, and a removable cover in connection with said slide which 55 engages said bearing to keep it in working position in the pocket.

12. In a roving frame, the combination

with a frame-head, front and rear bobbin-shafts, and bobbin-shaft bearings, of a vertically-moving traverse-rail slide close beside 60 the said frame-head having front and rear open-topped pockets for said bearings permitting vertical application and removal of the respective bearings, and a removable gear-box cover which engages said bearings 65 to keep them in working position in the pockets.

13. In a roving frame, the combination with a shaft, a compound-sleeve concentric with said shaft, a traverse-rail, a bobbin-shaft drive-mechanism extending between said compound-sleeve and the traverse-rail, and a cover enclosing said drive-mechanism, 70 swinging up and down in unison with the traverse-movements of the traverse-rail, of 75 a non-rotating bushing through which said shaft extends and upon which the rear portion of the cover rests, said bushing constituting a support for said rear portion.

14. In a roving frame, the combination with a shaft, a compound-sleeve concentric with said shaft, a traverse-rail, a bobbin-shaft drive-mechanism extending between said compound-sleeve and the traverse-rail, and a cover enclosing said drive-mechanism, 80 swinging up and down in unison with the traverse-movements of the traverse-rail, of 85 a bushing, held from rotation and from endwise movement, through which said shaft extends, upon which the rear portion of the 90 cover rests so that such portion is supported thereby, and with which said portion engages to prevent sidewise movement of the cover.

15. In a roving frame, the combination with a fixed portion of the machine-frame, 95 a bearing-plate applied thereto, a shaft, a compound-sleeve concentric with said shaft, a traverse-rail, a bobbin-shaft drive-mechanism extending between said compound-sleeve 100 and the traverse-rail, and a cover enclosing said drive-mechanism, swinging up and down in unison with the traverse-movements of the traverse-rail, of a non-rotating bushing through which said shaft extends, 105 held from endwise movement between said bearing-plate and the compound-sleeve, with the rear portion of the cover resting upon said bushing so as to support such portion, and with the said portion engaged with the 110 bushing so as to prevent sidewise movement of the cover.

GEORGE F. ALBRECHT.
HARRY BROOK.
